APPARATUS FOR THE TRANSMISSION OF
CURRENT PULSE COMBINATIONS, PAR-
TICULARLY FOR TELETYPEPING

Otto Moser, Bern, Switzerland

Application December 10, 1952, Serial No. 325,163
In Switzerland December 14, 1951

7 Claims. (Cl. 178—17)

1

My invention relates to apparatus for the transmission of current pulse combinations, particularly for teletyping.

Such apparatus have a group of selectively actuatable setting means, consisting in teletypewriters essentially of a keyboard with individually operable keys, for selecting a code combination corresponding to the particular message character to be transmitted. A number of pulse control members and correlated to the respective setting means or keys. The pulse control members may consist of revolvable cam discs that are firmly mounted on a common shaft or on different shafts driven by a motor. The pulse control cams become selectively effective to control an electric contact device for transmitting to the communication channel the trains of electric pulses corresponding to the various code combinations.

It has been proposed to provide the pulse-controlling cam discs in such apparatus with a lateral cam groove rather than with a peripheral cam configuration, the lateral cam grooves of the respective discs being differently shaped in accordance with the particular code combination assigned to each disc. Each cam disc coacts with an individual feeler which is normally outside the groove and enters it only when the pertaining setting means or key is being actuated. The particular feeler thus placed into cam engagement then acts as a cam follower during one full cam revolution and is thus caused to oscillate in a rhythm corresponding to the code combination assigned to the selected message character to be transmitted; and the electric contact device then closes and opens a circuit to issue corresponding electric pulses. An apparatus of this type, in contrast to those operating with a cam contour on the exterior cam periphery, has the advantage of a more reliable operation due to the fact that it eliminates contact-bouncing and reduces contact wear by the constrained guidance of the feelers, thus avoiding the pulse distortions resulting from such trouble. However, the pulse control apparatus with lateral cam grooves as heretofore proposed incur the drawback of imposing highly exacting requirements upon the accuracy of the cams, thus involving considerable manufacturing difficulties.

Although, in teletypewriter systems, slight deflections of the pulse combinations are usually corrected in the central or exchange stations, there are cases where the communication channel does not pass through such a station. This applies, for instance, to point-to-point traffic, i. e. to communication between two continuously interconnected teletype apparatus. In such cases, therefore, no possibility has heretofore been available of correcting any defective pulse combinations to the required degree of accuracy or to adapt them to any particular conditions of the communication channel.

2

It is an object of my invention to provide an apparatus for the transmission of current-pulse combinations that affords within its own mechanism a correction of deficiencies that may be due to inaccuracies in design or assembly of the pulse-control cams.

While the invention is hereinafter described with reference to apparatus in teletypewriters operating basically in the manner explained above, the invention is also applicable to any other devices for the selective transmission of code combinations in which a mechanical switching member, moving back and forth between two positions under control by a selectively actuated setting means, controls an electric pulse contact in accordance with the particular pulse combination to be issued.

According to my invention, I provide such a transmitting apparatus with two revolvable cam discs which are driven at constant speed during the operating period of the pulse control means. Each cam disc has cam flanks mutually spaced on the cam periphery in accordance with the pulse periods of the pulse combination to be issued. Two movable switching levers, engaging the respective cam discs, are moved between active and inactive positions due to the revolution of the cam discs, and thereby change the contact condition of the above-mentioned electric pulse contact, one lever effecting a change in one sense and the other lever in the opposite sense. I further provide the apparatus with locking means which, under control by the pulse-wise reciprocating switching member, alternately lock one of the two levers and simultaneously release the other lever, the phasing of the releasing operation being such that each lever, shortly after its release, reaches one of the cam flanks and hence can then move to its active position thus switching the pulse contact.

The foregoing and more specific objects and features of my invention will be apparent from the following description of the embodiment exemplified by the drawing, in which a pulse-combination transmitting apparatus for a teletypewriter is schematically shown in a perspective view.

The apparatus has a keyboard comprising a multiplicity of individual keys of which only one is schematically shown at 10. Firmly mounted on a shaft 13 are a number of pulse control discs, one for each key, of which again only one is illustrated at 14. Like all others, the disc 14 is provided with a lateral cam groove 27 whose cam contour is designed in accordance with the one pulse combination assigned to the particular pulse control disc. Each pulse control disc cooperates with a feeler member designed as a lever 41 which is tiltable about a pivot 11 and whose free end carries a feeler pin 42. Feeler member 41 has a bias in the counterclockwise direction.

When the key 10 is being depressed, it turns the lever 41 clockwise against its bias by a suitable connection (not illustrated) so that the feeler pin 42 enters into an entrance opening of groove 27 in plus control disc 14. This actuation also causes a start-stop drive (not shown) for revolving the shaft 13 to be started. During the revolution of the pulse control disc 14, the feeler pin 42 is caught and held in the groove 27 until a full revolution of disc 14 is completed. During the revolution of the pulse control disc 14, the feeler member 41 oscillates as its feeler pin follows the configuration of the cam groove. An arm 41a of feeler member 41 then causes a mechanical switching member 43 to also oscillate between two end positions in accordance with the pulse combination to be transmitted. The switching member 43 is pivotally mounted at 12 so that its oscillations occur in a plane parallel to the plane of illustration. The switching member 43 is common to all feeler members of the apparatus.

During the revolution of the pulse control disc 14, another shaft 18 is also revolving at constant speed. The shaft 18 may be driven from shaft 13, and for this purpose may, for instance, be coupled with shaft 13 or may form an extension thereof. Shaft 13 carries two cam discs 57 and 58. Each of these cam discs is equipped with cam flanks 57a or 58a which are spaced from each other on the periphery of each cam in accordance with the period of the pulses. The cam discs are further provided with cam portions 57b and 58b, respectively, which have a constant radius relative to the axis of revolution. The cam flanks 57a or 58a are located immediately behind the constant-radius cam portions 57b or 58b in the running direction of the cam disc (indicated by arrows). The cam flanks 57a and 58a have a steeply declining radius.

Two movable switching levers 46 and 47 are pivoted by respective pivot pins 15 and 16. Each lever is biased by springs, such as the spring assembly shown at 53 and 54, so as to be urged from opposite sides against the respective cam discs 58 and 57. The switching levers have a feeler nose 46b or 47b engaging the pertaining cam discs 58 or 57. Each lever is further equipped with a tappet portion 46a or 47a. During revolution of the cam discs 57, 58, the levers oscillate about their respective pivots, and the tappets 46a and 47a actuate a movable part 48 of a pulse switch in mutually opposing directions, the actuation being effected each time one of the levers 46 and 47 drops along one of the cam flanks to its active position.

The movable part 48 of the pulse switch is pivoted on a pivot pin 17 and carries a contact control piece 49 of insulating material. In one position of the movable switch part, the insulating piece 49 separates two stationarily mounted contact springs 50 with a contact 62. Mounted on the peripheral end of the movable part 48 is a detent 48a which coacts with a roller 51 movably journaled on a leaf spring 52, thus providing a snap action. The pulse contact device, therefore, operates as a snap-action switch. The stationary contact springs 50 are mounted on one leg of a U-shaped stationary holder 56 so that the position of springs 50 relative to the movable switch part 48 may be adjusted by means of a set screw 59 screwed through the other leg of holder 56.

The above-mentioned locking means for alternately locking one of the two switching levers 46,

47 while simultaneously releasing the other lever under control by the pulse-wise reciprocating switching member 43, comprise a teeter 45 revolvable about a pivot pin 55. The two arms 45a and 45b of the teeter are linked to respective locking rods 60 and 61 guided for longitudinal shifting motion. A third arm 45c of the teeter is straddled by a fork 44 mounted on the mechanical switching member 43. During reciprocating movements of the member 43, the locking rods 60, 61 are alternately shifted in their axial directions so that in each of the two end positions of member 43 one of the respective rods is placed in front of the pertaining switching lever 46 or 47 thus locking the lever while at the same time the other rod is withdrawn from the pertaining lever thus releasing that lever.

The cam discs 57 and 58 are so positioned relative to the cycle of movement of the control elements (pulse control disc 14) that the alternate release of the switching levers 46 and 47 occurs in an interval of time in which the feeler nose of the one switching lever being released at a time comes into the range of the constant-radius cam portion 57b or 58b preceding the cam flanks.

It will be understood that the keys 10 and the above-described elements 41, 43, 45, 46, 47, 48 are all movably mounted on a common stationary and rigid frame structure (not shown) on which the shafts 13, 18 are revolvable and the locking rods 60, 61 are slideable, and which also carries the spring means 53, 54, the holder 56 and the contact springs 50.

The operation of the apparatus is as follows. When key 10 is being depressed, feeler pin 42 of feeler member 41 is moved into the cam groove 27, and the same key operation causes the pulse control cam 14 to turn one revolution at constant speed, whereafter the feeler pin 42 is released to return into its original position. During the revolving period of pulse control cam 14, the feeler member 41, tracing with its pin 42 the groove contour, moves back and forth and imparts its oscillations through arm 41a to the switching member 43 common to all pulse control discs. Assume that member 43 just starts moving from its illustrated position in the clockwise direction and that this is to commence the issuance of an individual current pulse. The clockwise movement of member 43 is imparted through fork 44 and arm 45c to teeter 45. Hence teeter 45 oscillates accordingly. It withdraws the locking rod 60 from switching lever 46 thus releasing this lever. At the same time the teeter 45 advances the locking rod 61 thereby locking the switching lever 47. The released switching lever 46, under its spring bias, has its feeler nose 46b pressed against cam disc 57 at a point within the range of one of the cam portions 57b. As soon as the feeler nose 46b reaches the range of the next following cam flank 57a, this being the case when the cam disc 57 has turned a corresponding amount in the clockwise direction, the switching lever 46 reaches its active condition relative to the pulse contact device. That is, the switching lever 46, when dropping with its nose 46b along the cam flank, continues moving under its spring pressure so that tappet 46a tips the snap-action switch part 48 thus opening the contact 62 and establishing the "no current" condition. The switch part 48 is held in this switching condition by the resiliently mounted roller 51, while the switching lever 46, during the further revolution of cam disc 57, is returned to its original position.

In an analogous manner, the switching lever 47 is effective to actuate the movable switch part 43 in the opposite direction, again under control by feeler member 41 and pulse-control disc 14. The feeler nose 47b of lever 47 slides on a constant-radius portion 58b of cam disc 58 until the next-following cam flank 58a is reached. At this moment, the tappet 47a of switching lever 47 tips the switching element 48 to the other position thus establishing the "current" condition. Cam 57, therefore, always controls the start of a current pulse, and cam 58 always the end of the pulse.

The cam discs 57 and 58 are arranged on shaft 18 with such a mutual angular displacement that the two cam flanks successively scanned first on one and thereafter on the other cam during each full reciprocation of switching member 43, are spaced apart a distance corresponding to the length of the individual pulse. The cam discs 57 and 58, preferably, are angularly adjustable relative to each other on shaft 18 so that the moment when the switching levers reach the active condition may be adjusted relative to the cycle of movement of switching member 43. This permits advancing or retarding the operation of the pulse contact device so that the pulse duration may be adjusted within given limits. If the cam discs 57, 58 are arranged on the shaft 13 common to the pulse control disc 14, i. e. if shafts 18 and 13 are integral or interconnected, the cam discs 57, 58 are preferably also adjustable angularly with respect to the pulse control cams. The angular setting of the discs can then readily be calibrated so that each switching lever when released always drops first upon one of the cam portions 57b or 58b of constant radius.

It is apparent that, with a constant revolving speed of the cam discs 57 and 58, the current pulses being issued by the contact device have a constant pulse duration and constant pulse periods regardless of any inaccuracies with which the pulse control discs may be affected within certain limits. These limits are determined by the length of the constant-radius portions 57b and 58b of cam discs 57 and 58. No matter how large any time error in the stroke imparted to the switching member 43 may be, the desired pulse correction is always obtained, provided the feeler nose of the switching lever then being released will drop into the range of one of the constant-radius cam portions 57b or 58b. This condition, however, can be met without much effort.

In conjunction with the improvement in pulse transmission, it is significant that the number of the corrective cam discs need not, like that of the pulse control disc, correspond to the total number of code combinations, but that only two cam discs 57, 58 of high accuracy are needed for any number of pulse control discs 14 of lesser accuracy requirements. Besides, the exteriorly cammed discs can be more easily manufactured than the pulse discs with lateral grooves.

The pulse contact device, of course, may also be designed as a reversing switch to make the teletypewriter applicable for double-current (plus-minus) operation.

I claim:

1. Apparatus for transmitting current-pulse combinations, particularly in teletypewriters, comprising selectively operable control means, a mechanical switching member reciprocable between two positions under control by said control means in accordance with the pulse combination

to be issued, an electric contact device to be controlled by reciprocation of said switching member, two cam discs continuously revolvable during operation of said control means, each of said discs having cam flanks mutually spaced on the disc periphery in accordance with the pulse cycle periods, two movable switching levers engageable with the cam periphery of said responsive discs, said contact device having a movable switch part, and said levers having respective means engageable with said part for controlling said part in mutually opposing directions when the respective switching levers are controlled by said respective discs to move to an active position, and locking means having an element in engagement with said switching member and being selectively engageable with one of said respective levers for alternately locking one of said respective levers and releasing the other lever in accordance with the reciprocation of said switching member, each of said levers when released by said locking means being in said active position when entering into the range of one of said cam flanks.

2. In pulse-combination transmitting apparatus according to claim 1, each of said cam discs having cam portions of a constant radius relative to the axis of cam revolution, and said flanks being located directly behind said respective cam portions in the direction of cam revolution and having a steeply diminishing radius.

3. In a pulse-combination apparatus according to claim 2, said two cam discs having, relative to the cycle of movement of said control means, a phase adjustment wherein each of said switching levers at the release moment engages the starting point of one of said constant-radius cam portions ahead of one of said flanks.

4. In a pulse-combination apparatus according to claim 3, said control means comprising pulse-control discs having a common shaft on which said pulse-control discs are firmly mounted, said cam discs being also mounted on said shaft and being angularly displaceable relative to each other and relative to said pulse-control discs, whereby the moment when said levers reach said active position may be displaced relative to the reciprocating period of said switching member in order to adjust the pulse duration.

5. Pulse-combination apparatus according to claim 1, comprising spring means engaging said respective switching levers and having on said levers a force directed toward said respective cam discs so as to act through said levers upon said movable contact piece when said levers pass over one of said cam flanks.

6. Pulse-combination apparatus according to claim 1, comprising spring means urging said levers toward said respective cam discs, said locking means having a teeter coupled with said switching member to rock when said switching member is reciprocating, two axially displaceable locking rods linked to opposite sides of said teeter and alternately positioned on the cam-disc side of said respective switching levers for locking said levers.

7. In a pulse-combination apparatus according to claim 1, said contact device having snap-action means joined with said contact piece.

OTTO MOSER.
